UNITED STATES PATENT OFFICE.

JOB F. PEACOCK, OF NEW YORK, N. Y., ASSIGNOR OF ONE-HALF TO
ARTHUR W. PIERCE, OF HACKENSACK, NEW JERSEY.

MANUFACTURE OF MOLDED AND PLASTIC WARE.

SPECIFICATION forming part of Letters Patent No. 273,142, dated February 27, 1883.

Application filed August 24, 1882. (No model.)

To all whom it may concern:

Be it known that I, JOB F. PEACOCK, of the city, county, and State of New York, have invented new and useful Improvements in the Manufacture of Molded and Plastic Ware, of which the following is a specification.

This invention has for its object the ornamentation of molded or plastic articles, such as are made of clay or glass, chiefly for table-ware; and the invention consists chiefly in the method of uniting or fastening the ornaments or bands of metal upon the body of the vessel or cylinder without the use of any cement or adhesive substance, as will hereinafter appear.

15 In the drawings, Figure 1 is a cup in elevation, with a portion broken away at the top to show the section of the band of metal. Fig. 2 is a horizontal section through the plane at *a b*. Fig. 3 is a section through the plane *c d*.

20 When vessels are molded of clay, glass, &c., it is often desirable to fasten ornamental bands of metal upon their tops and bottoms, sometimes for attaching covers and handles and pedestals, &c. These bands have been fastened 25 in various ways, as by cement, or by screw-threads or some kind of locking devices, which generally expose the fastenings or soon become loose by frequent handling. Now, by this invention the parts are fastened together by

30 forming the interior of the bands and the exterior of the vessel with scroll-like surfaces in opposite directions, so that when the end of one is inserted into the other and turned around the inclines of the scrolls will be gradually forced upon each other, and thereby 35 wedge the parts together, holding them firmly by frictional contact.

At *A* is shown the body of a cup of cylindrical form, molded or formed of clay, porcelain, glass, or some similar substance, and upon 40 its upper end is fastened a band, *B*, made of metal, and the interior of said band is formed

in the scroll-like shape shown in section at Fig. 2 to fit upon a corresponding scroll formed upon the upper and exterior portion of 45 the vessel, also shown at Fig. 2. When the band so formed is placed over the end of the vessel and is slightly turned to produce a space, as seen at *C*, Fig. 2, then the two surfaces become wedged together firmly, and just in proportion to the amount of force applied in forcing the parts together. The bottom, at *D*, may also be fastened on in the same way, or the bottom of the vessel may have a scroll-pin, as at *E*, formed upon it to fit into a corresponding socket, as at *F*, in the metal bottom, or the bottom of the vessel may have its bottom inverted and a socket formed in it to correspond with a projecting pin or bearing-surface 60 extending from the metal bottom of the cup proper to fit in the socket in the bottom of the vessel, which is merely a reversal of the same principle of combining the parts.

I therefore claim—

1. The method of fastening metal bands upon 65 cups or cylinders of porcelain, glass, &c., by forming the inner surfaces of the bands in a scroll form, and the exterior of the vessel to correspond therewith in reverse, whereby they may be fastened together by rotating one upon 70 the other, as hereinbefore set forth.

2. A vessel formed of a plastic substance, as clay, porcelain, glass, &c., with a metal band having an interior surface in the form of a scroll to fit upon a corresponding surface upon 75 the vessel, as hereinbefore set forth.

In witness whereof I have hereunto subscribed my name and affixed my seal in the presence of two subscribing witnesses.

JOB FRANCIS PEACOCK. [L. S.]
